UNITED STATES PATENT OFFICE.

WILLIAM MARTAIN POND, OF GREENVIEW, ILLINOIS.

ADJUSTABLE AXLE.

No. 802,021.

Specification of Letters Patent.

Patented Oct. 17, 1905.

Application filed May 25, 1905. Serial No. 262,295.

To all whom it may concern:

Be it known that I, WILLIAM MARTAIN POND, a citizen of the United States, residing at Greenview, in the county of Menard and State 5 of Illinois, have invented a new and useful Adjustable Axle, of which the following is a specification.

This invention relates to the axles of vehicles, and has for its object to provide a simple-
10 constructed device of this character whereby by the transverse distance between the treads of the wheels may be increased or decreased as desired to equalize the wear upon roads or pavements and prevent the formation of ruts 15 or gullies therein.

With this and other objects in view, which will appear as the nature of the invention is better understood, the same consists in cer-
20 tain novel features of construction, as herein-
25 after fully described and claimed.

In the accompanying drawings, forming a part of this specification, and in which corresponding parts are denoted by like designating characters, is illustrated the preferred 25 form of embodiment of the invention capable of carrying the same into practical operation, it being understood that the invention is not necessarily limited thereto, as various changes 30 in the shape, proportions, and general assem-
blage of the parts may be resorted to without departing from the principle of the invention or sacrificing any of its advantages.

In the drawings thus employed, Figure 1 is a rear elevation of the improved device, partly 35 in section; and Fig. 2 is a plan view of the same.

In many parts of the country the softness of the ground causes the wheels of vehicles to form deep ruts in the roads, especially in rainy 40 weather, and renders the roads rough and unpleasant to travel over and seriously interferes with the passage of loaded teams there-
over, and the expense of keeping such roads in repair is a serious item in the tax-budget 45 of many communities. Many attempts have been made to prevent the formation of these objectionable ruts, such as widening the treads of the wagons, especially heavy farm-wagons; but this does not wholly prevent the forma-
50 tion of the ruts. To restore the uniformity of the surface of roads and prevent the formation of ruts of undue depth is the principal object of the present invention, which consists in providing means for altering the dis-
55 tance between the wheels, or what is known as

the "gage" of the vehicles, so that when the ruts become unduly pronounced the gage can be changed to prevent the vehicles from trav-
eling in the ruts, but forced to travel upon the "lands" at the sides of the ruts, thereby 60 causing the soil to crowd laterally into the old ruts and filling them and restoring the road to its former uniform surface. Then when ruts are again formed by the wider gage the wheels are restored to the standard gage and 65 the action repeated, and so on as often as re-
quired. Thus the roads are maintained in uniform condition by the very agency which formerly caused the inequality.

The improved device is applied to both axles 70 of the vehicle; but as the construction is the same for both axles it is shown applied to the rear axle only.

In applying the improvement the ordinary axle of the vehicle (represented at 10) is short-
ened either by sawing off the ends when the device is to be applied to vehicles already 75 constructed or forming the axles of less length than usual when applied to vehicles when manufactured. Attached beneath the shorter 80 axle 10 is a supplemental axle 11, preferably tubular, and secured thereto, as by clips 12 or other suitable means, and nearly equal in length to an ordinary axle. Slidably disposed upon the ends of the member 11 are hub- 85 skeins 13 14, having threaded studs on their outer ends for receiving the hub-holding nuts 15 16 and with spaced collars 17 18 at their inner ends, the collars to support rings 19 20, as shown. Pivoted at 21 to the axle member 90 10 is a plate 22, having rods 23 24 pivoted thereto at opposite sides and extended to forked members 25 26, the latter in turn pivoted at 27 28 to the rings 19 20. By this sim-
ple arrangement it will be obvious that when 95 the plate 22 is turned into one position the skeins 13 14 will be moved inwardly upon the member 11 and outwardly upon the same when the position is reversed. Thus the transverse distance between the treads of the 100 wheels may be altered to any required ex-
tent.

An operating-handle 29 extends from the plate 22, and suitable stops, such as pins 30, will be arranged for insertion in apertures 31 105 in the axle in the path of the handle to hold the handle and the parts associated therewith rigidly in adjusted position. In practice the plate 22, together with its connected rods and skeins, will be held only in entirely projected 110

or entirely withdrawn position; but for clearness of the illustration the plate and other parts are shown in intermediate position.

It will be obvious that the skeins and the 5 wheels carried thereby may be held at any desired point within the range of movement of the plate by providing a plurality of the apertures 31 spaced apart as required.

The member 11 will be provided with means, 10 such as pins, extending laterally therefrom and engaging longitudinal channels in the interior faces of the skeins for permitting the skeins to move longitudinally to the member 11, but prevented from rotation thereon, one 15 of the pins being shown at 34 and one of the channels in the skeins at 35; but it will be understood that each skein will be supplied with one of the channels and each member 11 with two of the pins, one near each end.

20 The device is simple in construction, can be applied to any of the various forms of vehicles, manufactured at small expense, and will operate effectually for the purposes described.

25 Having fully described the invention, what is claimed is—

1. The combination with a vehicle-axle, of hub-skeins mounted for longitudinal movement relative to the same, and means carried 30 by said axle for adjustably moving the skeins thereon and holding them in adjusted position.
2. The combination with a vehicle-axle, of hub-skeins mounted for longitudinal movement relative to the same, a plate mounted 35 for rotation on said axle, rods connected at one end to said plate at opposite sides of its

pivot and movably coupled at the other ends to said skeins, and means for actuating said plate and locking the same in any required position.

3. The combination with a vehicle-axle having lateral pins, of hub-skeins mounted for longitudinal movement relative to the same and provided with interior slots for engaging said pins, and means carried by said axle for 45 adjustably moving the skeins thereon, and means for holding them in adjusted position.

4. The combination with a vehicle-axle, of a supplemental member connected thereto and extending beyond the ends of the same, hub-skeins slidably disposed upon said member, and means carried by said axle for adjustably 50 moving said skeins upon said member and holding them in adjusted position.

5. The combination with a vehicle-axle, of 55 hub-skeins mounted for longitudinal movement relative to the same and provided with spaced annular ribs at the inner ends, collars engaging the skeins between said ribs, a plate mounted for rotation on said axle, rods connected at one end to said plate and at opposite sides of its pivot and movably coupled at the other ends to said collars, and means for actuating said plate and locking the same in position.

In testimony that I claim the foregoing as my own I have hereto affixed my signature in the presence of two witnesses.

WILLIAM MARTAIN POND.
